CLAIM

The ornamental design for a recliner chair, as shown and described.

DESCRIPTION

FIG. 1 is a front right perspective view of the recliner chair showing my new design.

FIG. 2 is a front view of the recliner chair.

FIG. 3 is a rear view of the recliner chair.

FIG. 4 is a left side view of the recliner chair.

FIG. 5 is a right side view of the recliner chair.

FIG. 6 is a top view of the recliner chair; and,

FIG. 7 is a bottom view of the recliner chair.

The broken lines illustrate portions of the recliner chair that form no part of the claimed design.

1 Claim, 7 Drawing Sheets

FIG. 1

FIG. 2

FIG. 3

FIG. 4

FIG. 5
